UNITED STATES PATENT OFFICE.

CARL A. SKALSTAD, OF CHICAGO, ILLINOIS.

UMBRELLA.

1,105,709.

Specification of Letters Patent.

Patented Aug. 4, 1914.

Application filed April 18, 1913. Serial No. 761,925.

To all whom it may concern:

Be it known that I, CARL A. SKALSTAD, a citizen of the United States of America, and resident of Chicago, Cook county, Illinois, have invented a certain new and useful Improvement in Umbrellas, of which the following is a specification.

My invention relates to an improvement in umbrellas, and more particularly to the provision of a construction which enables the center of the umbrella to be held directly over the center of the head of the user.

In ordinary constructions, where a straight rigid rod or staff is employed, it is, of course, impossible for the user to stand directly in the center of the umbrella. By my construction, I employ a jointed rod which, after the umbrella has been raised, is capable of being supported in an off-set position, so that all parts of the person are equally protected from the rain or sun, as the case may be.

The character of my invention will be more readily understood by having reference to the accompanying drawings, in which—

Figure 1 is a sectional view showing the umbrella in raised position. Fig. 2 is a detail view of a part of the center rod showing the manner in which the umbrella is held in raised position. Fig. 3 is a sectional view taken on the line 3—3 in Fig. 5. Fig. 4 is a detail view, partly in section. Fig. 5 is a further detail view of a portion of the center rod showing the manner in which it is supported in its off-set position. Fig. 6 is a detail view of the upper portion of the center rod. Fig. 7 is a sectional view taken on the line 7—7 of Fig. 5. Fig. 8 is a sectional view taken on the line 8—8 of Fig. 6. Fig. 9 is a detail view of a portion of the center rod.

Throughout the drawings similar reference characters refer to similar parts.

The umbrella illustrated is of the usual construction comprising the cover 11 mounted on ribs 12 secured to the center rod or staff 13 with suitable braces 14, secured to the runner 15 which slides along the rod 13. This runner is provided with a spring catch 16 which is provided with a hooked end portion 17 adapted to engage with the projecting lug 18 carried by the rod 13. This rod, instead of being composed of a single section, as in the usual construction, is divided into a plurality of sections, which sections

are suitably hinged together. The upper portion of this rod comprises a hollow cylindrical staff 19 within which the lower section 20 is adapted to slide. Telescoping within the section 20 is the link 21 which at its upper end is secured to the link 22, which in turn is secured by the wire 23 to the upper end of the staff 13. These links 21 and 22 are hinged together in any suitable manner, and the link 21 has secured thereto a wire 24 provided with an enlarged end portion 24^a. A bent wire 25 in the section 20 of the rod is adapted to engage with this stop 24^a, so as to prevent this link 21 being withdrawn from the rod 20. Furthermore, this wire 25 is so arranged within the rod 20 that it prevents the flat link 21 from turning freely within the rod.

When the umbrella is in closed position, the sections of the rod are in alinement, and the section 21 telescopes within the section 20, and the upper portion of the section 20 telescopes within the portion 19, as clearly shown in Fig. 4. A latch 26 is provided on the upper end of the rod 20, which latch engages with a suitable locking notch 27 in the lower end of the portion 19 of the center rod. A spring 28 is employed to normally maintain this latch in position to engage with this notch so as to lock the parts together.

In opening the umbrella, the runner 15 is first slid upward along the section 20 of the rod, and then over a portion of the section 19 until the spring catch 16 engages with the locking projection 18. The rod 20 is then grasped by the sleeve 29 on the rod 20 and rotated, this portion being roughened or knurled for this purpose. This rotation disengages the catch 26 from the notch 27, and this permits the rod 20 to be drawn downward out of engagement with the upper section 19 and until the wire stop 24^a engages with the wire 25. The lower portion of the section 19 is provided with a slot on one side thereof, while the upper end of the rod 20 is provided with a corresponding slot on the opposite side. By this construction, when the rod 20 has been drawn downward so that it has disengaged itself from the upper portion of the rod 19, it can then be swung laterally, the link 21 swinging around the pivotal connection with the link 22, the slots in the two portions 19 and 20 serving as guides for this link 21. The rod 20, after being swung laterally, is then

swung upwardly so that the upper end 30 of this rod 20 passes through the loop 31 formed in one of the braces 14. To further support the rod 20 in this off-set position, 5 there is provided a swinging link 32 pivoted at one end to the rod section 19, and at its outer end being pivoted to a second link 33 secured to one of the ribs 12. This link 33 is so positioned that when the umbrella is 10 in raised position it is located immediately above the opening 31 in the brace 14. The end 30 of the rod 20 being channeled, slides over this link 33 and is thus rigidly and firmly held in place.

15 When it is desired to close the umbrella, it is merely necessary to pull downward upon the rod 20, so as to disengage it from the brace 31 and to then swing the same into alinement with the section 19 and to 20 again telescope the sections one within the other. The runner 16 can then be slid down the rod in the usual manner.

It will be noticed that when the umbrella is in raised position that the link 21 is inclined upwardly, and in this manner is entirely out of the way and does not interfere with the umbrella being carried directly over the head of the user, and the umbrella can be lowered to such a point that the lower 30 portion of the section 19 of the staff is a short distance above the head. Furthermore, it will be seen that the rod 20 is firmly and rigidly secured in its off-set position so that a very firm and efficient construction is obtained.

While I have illustrated and described one particular embodiment of my invention, it will, of course, be understood that various changes and modifications will readily suggest themselves to those skilled in the art 40 and still come within the scope of my invention.

What I claim as my invention is:

1. An umbrella comprising a sectional staff, ribs secured to said staff, a runner 45 sliding on said staff and provided with braces secured to said ribs, means for hold-

ing said runner on the upper portion of said staff, thereby holding said umbrella in open position, said staff comprising an upper section, and a lower section telescoping within said upper section, said lower section adapted to be drawn downward and then swung laterally into a position out of alinement with said upper section, a loop 55 in one of said braces, said lower section adapted to be swung upwardly so that its upper end projects through said loop, and a guiding link pivoted at one end to one of said ribs and adapted to engage with the 60 upper end of said rod section when thus moved upwardly whereby said rod is supported in its off-set position, and a link connecting the opposite end of said guiding link to said staff.

2. An umbrella comprising a sectional staff having an upper and a lower section, ribs secured to said upper section, said lower section adapted to be swung into a position out of alinement with said upper section, and a guiding link pivoted at one end to one 65 of said ribs and connected at its opposite end by a second link to said staff for supporting said lower section in offset position.

3. An umbrella comprising a sectional 70 staff having an upper and a lower section, ribs secured to said upper section, said lower section adapted to be swung into a position out of alinement with said upper section, a guiding link pivoted at one end to one of 75 said ribs and connected at its opposite end by a second link to said staff for supporting said lower section in offset position, a runner sliding on said staff and provided with braces secured to said ribs, and a loop in one 80 of said braces through which the upper end of said lower section is adapted to pass.

Signed by me at Chicago, Illinois, this 15th day of April, 1913.

CARL A. SKALSTAD.
